UNITED STATES PATENT OFFICE.

JEAN-MARIE WERNER, OF MONTBELIARD, FRANCE

SHAVING BRUSH.

Application filed January 31, 1927, Serial No. 164,916, and in France February 27, 1926.

My invention relates to hygienic shaving brushes comprising sets or bunches of bristles which are inclosed in a protecting sheath and are used only once in order to prevent all 5 contagion between persons. The bunches or sets of bristles are mounted in place upon a suitable handle at the time of use, and my invention relates to the construction of a handle for this purpose, which provides for 10 the ready insertion and removal of the sets of bristles and will also prevent the use of the bristles a second time.

The bristles (or fibres) are held together before use by means of a metal ring attached 15 by clips, or by suitable binding members such as wires, braiding, paper rings or the like. To properly mount the bristles in the handle so that none of them will escape from the bunch, the said handle should exercise 20 pressure upon the whole periphery of the bunch. According to my invention, the handle comprises a socket or sleeve of cylindrical, tapered or like shape, into which the set of bristles is inserted, the latter being held 25 in place by inserting a tapered spindle into the set, by which it will be expanded, thus expanding or bursting the element which binds the bristles together, so that they cannot be used a second time.

30 The appended drawings show by way of example various embodiments of the invention.

Fig. 1 is an axial section of a handle provided with a tapered spindle.

35 Fig. 1^a is a modified form of spindle.

Figs. 2 and 3 represent modified forms of this device.

In Fig. 1, 1 is the handle properly so called, into the lower end of which is screwed the 40 spindle 2 maintained by the pin 3.

The said spindle comprises a screw-threaded part 4 engaging a tapped sleeve 5 which is mounted by easy friction upon the end of the handle 1; the end 6 of said spindle 45 is tapered and screwthreaded, and this end is adapted for insertion into the bunch of bristles (or fibres) 7 whose bottom part is fitted into the recess 5^a formed in the sleeve 5. The interior of the sleeve 5 is preferably 50 striated to prevent the rotation of the bristles when the spindle 2 is screwed in place.

In this device, it will be noted that during the insertion of the tapered end 6 into the set

of bristles, these latter will expand and will cause their maintaining ring 8 to burst, so that the said ring will be jammed upon its entire periphery against the inner striated surface of the recess 5^a. The screw-thread should have the same pitch for the part 4 and for the end 6, so as to prevent all relative motion of the set of bristles and the sleeve 5 when the device is screwed.

Since the tapered end 6 is more readily inserted into the bristles at the beginning of the operation, by reason of the small cross section of the tapered end, adjacent the point, I may, in order to screw the device more rapidly, adopt for the coacting parts 4 and 6 a variable pitch which is greater near the point than at the other end. I may further provide upon the tapered part (Fig. 1^a) a multiple screw-thread, and on the part 4 a single screw-thread whose pitch is that of the thread of the said tapered part, since experience shows that a tapered end thus disposed will enter the fibres more readily; or otherwise, I may provide multiple threads in all circumstances.

It should be noted that in this device, since the binding of the bristles is broken, it will be practically impossible to remove the bristles from the handle without dispersing them, so that it will not be feasible in practice to further bind up the bristles, 85 to pack the same and to place them on the market.

In the modification shown in Fig. 2, the tapered and threaded spindle 9 is riveted at 10, for instance, to the handle 11 and it maintains upon this part a concave member 12 which serves as an extension for the said handle and carries an outer screw-thread of the same pitch as the thread of the handle. To the said concave member is 90 screwed a cap 13 with internal thread, whose upper part is pressed into the shape of a socket or cap 14 with perforated end, into which the bristles 7 are inserted. Upon screwing the said cap upon the concave member 12, the bunch of bristles, which is held in the hand together with the cap, is screwed upon the said spindle, so that it will expand 95 and will exercise a strong pressure upon the cap 14.

In Fig. 3, the sleeve 15 is slidable and rotatable on the cylindrical part of the spindle 16, and herein the screwthreaded tapered

end 17 of said spindle is inserted into the fibres solely by screwing the set of bristles upon the said tapered end.

Having thus described my apparatus, 5 what I claim as new therein, and my own invention, is:—

1. A shaving brush-holder comprising a handle, a sleeve upon said handle, the said sleeve being adapted for the insertion of the 10 base portion of a bundle of bound up bristles and a tapered spindle secured to the said handle and adapted to enter into the said bundle of bristles, the said sleeve comprising a cylindrical extension which is internally provided with a screw thread, the tapered surface of the said spindle being provided with a screw thread and said spindle comprising a screw threaded cylindrical extension which is adapted to be screwed 15 into the extension of the said sleeve, the pitch of the screw thread of the said exten-

sion being the same as that of the one on the tapered portion of said spindle.

2. A shaving brush holder comprising a handle, a sleeve upon the said handle, the 25 said sleeve being adapted for the insertion of the base portion of a bundle of bound up bristles and a tapered spindle secured to the said handle and adapted to enter into the said bundle of bristles, the tapered surface of the said spindle being screw threaded, the said sleeve comprising a cylindrical extension which is hollow, the said spindle comprising a cylindrical extension adapted to enter smoothly into the cylindrical extension of the said sleeve, in such manner that the spindle is guided, but may rotate and move axially relatively to the said sleeve.

In testimony whereof I have hereunto af- 40 fixed my signature.

JEAN-MARIE WERNER.
